UNITED STATES PATENT OFFICE

JOHN T. SCULLY, OF NEW YORK, N. Y.

DESIGN FOR A COMBINED SAFETY-RAZOR HANDLE, BLADE SUPPORT, AND GUARD

Application filed February 5, 1930. Serial No. 34,409. Term of patent 14 years.

To all whom it may concern:

Be it known that I, JOHN T. SCULLY, a citizen of the United States, residing at New York city, in the county of New York, State of New York, have invented a new, original, and ornamental Design for a Combined Safety-Razor Handle, Blade Support, and Guard, of which the following is a specification, reference being had to the accompanying drawing, forming a part thereof.

Figure 1 is a side view of a combined safety

razor handle, blade support, and guard embodying my new design.

Figure 2 is a side view of same with the support and guard turned through an arc of 90°.

I claim:

The ornamental design for a combined safety-razor handle, blade support, and guard, as shown.

JOHN T. SCULLY.
